[57] CLAIM

The ornamental design for a reflectorized marker, substantially as shown and described.

DESCRIPTION

FIG. 1 is a front perspective view of a reflectorized marker embodying my design;
FIG. 2 is an inverted rear perspective view thereof;
FIG. 3 is a side elevational view;
FIG. 4 is a top plan view thereof;
FIG. 5 is a front elevational view thereof;
FIG. 6 is a sectional view on an enlarged scale taken along the line VI—VI of FIG. 5.
